HARRY CARPENTER STEARNS, OF OAK PARK, ILLINOIS, ASSIGNOR TO WESTERN ELECTRIC COMPANY, INCORPORATED, OF NEW YORK, N. Y., A CORPORATION OF NEW YORK

APPARATUS FOR ARRANGING ARTICLES

Application filed February 27, 1926. Serial No. 91,280.

This invention relates to methods of and apparatus for arranging articles, and more particularly to methods of and apparatus for arranging parts in predetermined positions for assembly purposes.

Where parts must be arranged in predetermined positions for assembly purposes or the like, it is common shop practice in some instances for a worker to manually select parts or articles from an indiscriminately arranged supply thereof and subsequently, in accordance with a definite plan or system of operation, place the articles thus selected in properly arranged positions. One example of such practice may be found in the art of manufacturing electro-magnetic induction coil spools extensively used in telephone systems. The core portions of certain types of these spools comprise a plurality of elongated, metallic laminations of magnetic material which are snugly fitted within a suitable frame or tube. It has heretofore been the practice in some instances for the worker to select an approximate number of laminations from an indiscriminately arranged supply thereof which it is estimated will completely fill and snugly fit into a companion frame or tube. Under such circumstances it becomes necessary for the worker to properly orient or otherwise arrange the laminations thus selected in a definite order or group for facilitating the subsequent assembly thereof with a companion tube.

Objects of the present invention are to provide improved and simple methods of and apparatus for effectively and efficiently advancing indiscriminately arranged articles and arranging the advanced articles in proper predetermined positions.

In order to obtain these and other objects and in accordance with the general features of the invention an apparatus representing one embodiment of the invention and by means of which the improved method may be practiced, is provided which has a pair of specially formed screw mechanisms, inclined from the horizontal and rotatably mounted at their opposite ends. These mechanisms are formed with spiral grooves resembling square thread structures which are adapted to accommodate

core laminations. These core laminations are placed indiscriminately within a hopper so as to superimpose the lower extremities of the screw mechanisms and upon rotation of the screw mechanisms in opposite directions 55 the lowermost laminations adjacent to the upper surfaces of said mechanisms lodge themselves within the continuously aligned spiral grooves and are subsequently urged or advanced away from the continuously agitated mass of laminations. As the laminations lodged within the grooves are advanced, they are directed between gauge pins which prevent the feeding of distorted or imperfect laminations into a stacking device provided 60 at the upper extremities of the screws. When a composite group of laminations of predetermined magnitude becomes stacked by the upper extremities of the screws, the stacking device deposits the group in specially formed 65 spiral grooves formed at the extremities of the screws and the continued rotation of said screws advances and delivers the group to a suitable magazine. Upon being completely loaded with composite groups of laminations 70 the magazine may be removed to an assembly position or apparatus and replaced by an empty magazine.

Other objects and features of this invention will be readily apparent from the following detailed description when considered with the accompanying drawings, in which

Fig. 1 is a vertical longitudinal section of an arranging apparatus disclosing one embodiment of the invention with a supply of 85 core laminations deposited within the hopper;

Fig. 2 is an enlarged fragmentary sectional detail of the upper end of the apparatus as shown in Fig. 1, with the stacking device thereof shown in section on a line approximating the inner wall of the hopper to more clearly expose the latching mechanism of said stacking device;

Fig. 3 is a fragmentary plan view of the lower end of the hopper disclosing the promising arrangement of a supply of laminations deposited therein;

Fig. 4 is a transverse sectional detail of the lower portion of the stacking device taken on the line 4-4 of Fig. 1;

Fig. 5 is an end elevational view of the arranging apparatus taken on the line 5—5 of Fig. 1, with the magazine removed therefrom;

5 Fig. 6 is a plan view of the screw mechanism taken perpendicular to the plane of said mechanism with the stacking device broken away to expose structures otherwise hidden;

10 Fig. 7 is a perspective view of a form of core member adapted to be arranged by the apparatus;

15 Fig. 8 is a view somewhat similar to the view shown in Fig. 2 and discloses a modified form of an arranging apparatus embodying the invention, and

Fig. 9 is an end elevational view taken on the line 9—9 of Fig. 8.

Referring to the drawings wherein like numerals designate similar parts throughout the various views, it will be observed that the arranging apparatus includes a base 10 having an upper surface inclined from the horizontal and designed to support a suitable hopper 11. A pair of angularly related screw mechanisms 12, longitudinally disposed within the hopper 11 and arranged in parallelism with the inclined upper surface of the base 10, are revolvably mounted at their upper and lower extremities in suitable bearing members 13 and 14, respectively. The lower extremity of each screw mechanism 12, adjacent to the bearing member 14, is provided with a gear 15, the lower end of one screw mechanism (left Fig. 6) being formed with an extended 35 shaft portion which projects through the rear wall of the hopper 11 and carries a suitable drive pulley 17 at its outer extremity (Fig. 1). The rotation of the pulley 17, occasioned by a belt operated by any suitable 40 driving means (not shown), will result in imparting reversed rotation to the screw mechanisms 12 (see arrows Figs. 5 and 9) through the medium of the gears 15.

45 Mounted adjacent to the pulley 17 is a disk 18 (Fig. 1) with the inner face thereof formed with a plurality of cam teeth 19. These cam teeth 19 are designed for engagement with a roller 20 mounted in a bracket 21 secured to the lower or rear surface of an 50 agitating plate 22 hingedly mounted at its upper end and traversing the rear end of the hopper 11. The rotation of the disk 18 swings the agitating plate 22 about its hinge, the roller 20 engaging with and being actuated by the cam teeth 19 of the disk 18. This 55 agitating effect will be more clearly understood as the description progresses.

The hopper 11 is adapted to accommodate elongated core members or laminations 23 60 which, when deposited therein, rest upon the front surface of the agitating plate 22 and the upper surface of the lower extremities of the screw mechanisms 12. Spiral ways or grooves 24 formed in the screw mechanisms 12 65 are sufficient in width and depth to accommo-

date a lamination and it will be clear from the structure disclosed in Fig. 6 that the angular relation or disposition of the axes of the screws is such that the uppermost portion of the grooves in one screw will always be in alignment with companion or corresponding grooves in the other screw. This alignment permits a lamination disposed transversely above the screw mechanism 12 to be carried upwardly within the hopper 11 when it becomes lodged within a pair of the aligned grooves 24. Gauge pins 25 provided on the opposite walls within the hopper 11 are so positioned that when a core member 23 is advanced by the screw mechanisms 12, the upper end surfaces of the core member thus advanced will pass immediately beneath the gauge pins 25, providing that the members are properly positioned and that the ends thereof are not bent upwardly. The core 85 members which are bent or distorted upwardly at their ends strike the gauge pins 25 and are thereby completely dislodged from the grooves 24. Similar gauge pins 26 (dotted lines Figs. 1 and 2) positioned immediately below the plane of the upper surface of the screw mechanism function in like manner to automatically reject core members which are distorted or bent downwardly at their extremities. It is to be understood that 90 these pins 25 and 26 likewise function to completely dislodge or properly rearrange a core member which is improperly positioned upon the screws as it approaches the pins.

The upper portions of the hopper side walls are formed with brackets 27 which supply a hinged mounting at their upper outer extremities for a depending gate member 28 of a stacking device denoted generally by the numeral 29. An opening 30 (Fig. 5) extends 100 upwardly from the lower enlarged portion of the gate member 28 at each end thereof, and plungers 31 slidable within the opening 30 support a latch bar 32 at their outer ends. The movement of the plungers 31 within their respective openings 30 is limited by a screw 33 which extends into each opening 30 and supplies a stop which is adapted for engagement with the upper and lower shoulders formed at the ends of a recess 34 provided in the plungers. Springs 35 interposed between the end of the plungers 31 and the inner extremity of their respective openings 30, together with a coil spring 36 positioned intermediate the lower portion of the gate 105 28, serve to yieldingly retain the latch bar 32 in its extended position as disclosed in Figs. 2, 3, and 5. Referring to Figs. 2 and 4 it will be observed that a latch 37 suitably secured to the wall of the hopper 11 is adapted for engagement with one end of the latch bar 32 (left Fig. 4) when the gate 28 assumes a position perpendicular to the axial plane of the screw mechanisms 12. By means of 110 springs 38 (Fig. 1) coiled about stop pins 115 39, the latch 37 is held in its extended position when the gate 28 is in its normal position. The 120

39 secured to brackets 40 suitably mounted upon the lower portions of the hopper brackets 27, the latch bar 32 is yieldingly held in engagement with the latch 37 (Fig. 2). It will be apparent that when the latch bar 32 is moved upwardly beyond the upper portion of the latch 37, the gate 28 will be swung upwardly by the action of the springs 38, this upward swinging movement being limited and arrested by the heads of the screw stops 39. To relatch or re-engage the bar 32 it is only necessary to swing the gate 28 downwardly against the action of the springs 38.

A stacker plate 41 (Fig. 5) is secured to the lower extremities of a pair of plungers 42 slidably mounted within the lower portion of the gate 28 and intermediate the ends thereof. These plungers 42 are similar to the latch bar plungers 34 and are limited in movement by means of screws 43 and urged outwardly by means of springs 44 (Fig. 5). This stacker plate 41 is disposed slightly below the plane of the upper surface of the screw mechanisms 12 and operates in connection with specially formed screw threads or grooves at the upper extremity thereof. As hereinbefore mentioned, a lamination 23 which becomes lodged within the grooves 24 of the screw mechanisms 12, is conveyed upwardly along an inclined plane and it will be observed that as a lamination approaches the stacker plate 41 the depth of the groove 24 is increased (Figs. 2 and 3) to permit the lamination to pass therebeneath. Beyond this point the groove 24 experiences an abrupt decrease in depth and in fact during a fraction of a turn of the screw, starting from the point where the lamination enters beneath the stacker plate 41, the depth of the groove 24 is decreased to such an extent that the lamination advanced during this portion of the turn is carried upwardly into a plane coincident with the uppermost surface of the screw mechanisms. As this advanced lamination is carried upwardly against the stacker plate 41 it becomes lodged between a pair of depending guide members 46 (Figs. 4 and 5) formed near the ends and at the lower enlarged portion of the gate 28. Each subsequent revolution of the screw mechanisms 12 will result in advancing a lamination into position beneath the lamination just previously stacked between the guide members 46. This stacking operation results in urging the stacker plate 41 upwardly against the action of the springs 44 and by continued movement thereof the stacker plate will be carried into engagement with the latch bar 32 and when the number of stacked laminations attains a predetermined magnitude the latch bar 32 becomes disengaged from the latch 37, and the gate 28 will swing forwardly and the composite group of laminations stacked therein will thereby be conveyed forwardly along the surface of the screw mechanisms 12. This swinging of the

gate 28 is sufficient to cause the composite group of stacked laminations to be conveyed and deposited by gravity into specially formed deep grooves 47 provided at the upper extremity of the screw mechanisms 12. The continued rotation of the screw mechanisms will advance the deposited laminations into the lower end of a magazine 48, traversing the upper portion of the hopper 11 and detachably mounted within suitable slots formed in the walls thereof. Leaf springs 49 suitably secured to the walls of the hopper 11 are positioned so as to engage with the upper surface of each advancing stack of laminations as they approach the lower end of the magazine 48 to insure the delivery of the stack to the magazine in compact form.

Secured to the lower forward surface of the gate 28 are a pair of cam lugs 51 (Fig. 4). These cam lugs 51 are designed to be engaged by companion pins 52 secured near the upper extremity of each screw mechanism 12 and extending radially therefrom. It is to be understood that following the forward swing of the gate 28 these pins 52 engage with the respective surfaces of the cam lugs 51 and thereby cause the gate 28 to swing downwardly and become relatched in position to receive another composite group of laminations. A pin 50 similar to the pin 52 (Fig. 6) is secured to each screw mechanism at a point adjacent to the groove which is designed to lower an advancing lamination beneath the stacker plate 41 as hereinbefore described and serves to positively prevent a lamination which may be improperly positioned at this point, to be further advanced without being properly rearranged in position. These pins 50 will either completely dislodge the improperly positioned lamination or cause it to be rearranged.

In Figs. 8 and 9 a modified form of the invention is disclosed which employs a similar type of screw mechanism for advancing and stacking core laminations. A screw mechanism 53 is provided with a spiral groove 54 which is similar in design and functional characteristics to the groove 24 described in connection with the screw mechanism 12. The upper extremity of the screw mechanism 53 corresponds to the structure of that portion of the screw mechanism 12 which serves to stack the advanced laminations against the stacker plate 41 and between the guide members 46. It will be apparent that these guide members 46 have been supplanted in the apparatus disclosed in Figs. 8 and 9 by a fixed chute 54 which is designed to detachably support a magazine 55. The screw mechanisms 53 are adapted to select and advance laminations from an indiscriminately arranged group thereof (not shown) in the manner heretofore described in connection with the screw mechanisms 12 and cause the advanced laminations to become stacked within the

fixed chute 54 and eventually within the magazine 55 associated therewith. The front side of the chute 54 is provided with a cover plate 56 which is detachably secured thereto by means of suitable spring clips 57 and the magazine 55 is likewise secured in position by means of similar spring clips 58. A weight 59 is employed to insure compact stacking of the laminations within the magazine 55.

10. In the operation of the arranging apparatus the core laminations of the type disclosed in Fig. 7 are placed indiscriminately within the hopper 11 as shown in Figs. 1 and 3 and rotation is imparted to the screw mechanism 12 by application of power to the pulley 17 from any suitable source. By the engagement of the cam teeth 19 of the disk 18 with the roller 20 a jogging or vibratory movement is imparted to the agitating plate 22. This agitates the laminations 23 within the hopper 11 and as a result the lowermost laminations become self-lodged within the grooves 24 of the screw mechanism 12. In this connection attention is invited to the fact that the surface of the screw mechanisms adjacent to the leading portion of the grooves has been chamfered, this being done to facilitate the self-lodging 25 of the laminations within the grooves. If a lamination improperly traverses the screw mechanism upon being advanced from the supply within the hopper, as shown in Fig. 3, continued rotation of the screws will cause 30 it to fall back into proper arrangement, lodged within a pair of aligned ways or grooves 24. As the laminations 23 are advanced upwardly along the inclined plane of the mechanisms 12 they are directed between the pair of gauge pins 25 and 26 which 35 serve to reject and thereby prevent the further advancement of imperfect or distorted laminations. Should a lamination be improperly positioned upon the screw mechanisms as it approaches the upper extremity thereof these gauge pins 25 and 26 will either 40 completely dislodge the lamination and cause it to fall back into the bottom of the hopper or they will effect the immediate proper arranging or positioning thereof within a pair 45 of aligned grooves 24. The laminations which are permitted to pass between these gauge pins are advanced into position beneath the stacker plate 41 and by continued 50 rotation of the screw mechanisms a composite group of laminations are stacked upwardly against the stacker plate and become lodged between the depending guide members 46 formed at the lower end of the gate 55 55. 28. When a stack of laminations of predetermined magnitude become lodged within the gate 28 the disengagement of the bar and latch members 32 and 37, respectively, serve to permit the gate to swing forwardly and 60 the laminations thus stacked to be conveyed 65

and deposited in the deep groove 47 provided at the upper extremity of the screw mechanisms 12. Continued rotation of the screw mechanisms causes the stack of laminations deposited within the groove 47 to be advanced 70 and inserted within the magazine 48 and the advancing of the composite groups of laminations are continued step by step until the magazine 48 is completely filled, at which time it may be replaced by an empty magazine. 75

The operation of the modified form of arranging apparatus shown in Figs. 8 and 9 is the same in principle as the operation just described, the only difference being that the mechanism 53 disclosed in these figures serves to continuously stack the laminations within the magazine 58 as distinguished from the arranging apparatus first described wherein composite groups of laminations of predetermined magnitude are stacked and subsequently delivered to a magazine. 80

Although the invention as herein illustrated and described is particularly well adapted for use in connection with apparatus for arranging and assembling core members and the like, it should be understood that the novel features thereof are capable of other applications and should be limited only by the scope of the appended claims. 85 90 95

What is claimed is:

1. In an apparatus for arranging articles, a receiving means, a screw mechanism associated therewith designed to receive and advance articles and to deliver the advanced 100 articles in proper predetermined position to the receiving means, and means carried by the screw mechanism adapted to prevent improperly positioned articles from being advanced to the receiving means. 105

2. In an apparatus for arranging articles, a screw mechanism having a portion to receive and advance articles and a portion to arrange and deliver the advanced articles in group formation. 110

3. In an apparatus for arranging articles, a screw mechanism having a portion to receive and advance articles and a portion to subsequently stack the advanced articles. 115

4. In an apparatus for arranging articles, a screw mechanism having a portion to individually select and advance articles from a supply thereof and a portion to arrange the advanced articles in group formation. 120

5. In an apparatus for arranging articles, a screw mechanism having a portion to individually select and advance articles from a supply thereof and a portion to stack the advanced articles. 125

6. In an apparatus for arranging articles, a screw mechanism having a portion to individually select and advance articles from an indiscriminately arranged supply thereof and a portion to arrange the advanced articles in composite order. 130

7. In an apparatus for arranging articles, a mechanism provided with a spiral way having a portion thereof adapted to receive and advance members and a portion thereof to form the advanced members into a composite group, and means for actuating the mechanism. 50
8. In an apparatus for arranging articles, a hopper, a mechanism associated therewith provided with a spiral way having a portion thereof adapted to select and advance articles within the hopper and a portion thereof to subsequently stack the advanced articles, and means for actuating the mechanism. 10
9. In an apparatus for arranging articles, a receiver, a hopper, a screw mechanism associated with the hopper and designed to select and advance articles from within the hopper and to form the advanced articles 20 into a composite group and deliver said group to the receiver, means for predetermining the magnitude of the formed composite group, and means for actuating the mechanism. 15
10. In an apparatus for arranging core members and the like, a magazine, a hopper, a mechanism within the hopper formed with a spiral way adapted to select and advance core members from within the hopper and 30 to arrange the advanced core members into a composite group and to advance the composite group within the magazine, means for rejecting imperfect core members selected by the mechanism, and means for actuating the mechanism. 35
11. In an apparatus for arranging articles, a magazine, a pair of screw members associated therewith having angularly related axes and adapted to receive and advance articles 40 and to feed the advanced articles in composite order to the magazine, and means for actuating the screw members. 45
12. In an apparatus for arranging articles, a screw mechanism, means for associating articles with the screw mechanism in an indiscriminate arrangement, said screw mechanism having means for changing the indiscriminate arrangement to a predetermined arrangement, and means for subsequently rearranging the articles. 50
13. In an apparatus for arranging articles, a screw mechanism, and means for associating articles with the screw mechanism in an indiscriminate arrangement, said screw mechanism having means for changing the indiscriminate arrangement to a parallel arrangement, and means for changing the parallel arrangement to a composite arrangement. 55
14. In an apparatus for arranging articles, a receiving means, and a screw mechanism associated therewith having a portion for properly arranging and advancing articles 60 and a portion for rearranging the advanced 65
- articles into proper predetermined position for delivery to the receiving means. 70
15. In an apparatus for arranging articles, a receiving means, and a screw mechanism associated therewith having a portion for properly arranging and advancing articles from an indiscriminately arranged supply thereof and a portion for rearranging the advanced articles into group formation for delivery to the receiving means. 75
16. In an apparatus for arranging articles, a screw mechanism having a portion for receiving and advancing articles and a portion for stacking the advanced articles, and means for preventing imperfect articles from being 80 stacked by the screw mechanism. 80
17. In an apparatus for arranging articles, a receiving means, a pair of oppositely rotatable screw members having cooperating portions for arranging and advancing articles 85 from an indiscriminately arranged supply thereof and cooperating portions for rearranging the advanced articles and delivering them to the receiving means, and means for actuating the screw mechanism. 90
18. In an apparatus for arranging articles, a rotatable member having a spiral way comprising a portion for properly arranging and advancing articles from an indiscriminately arranged supply thereof and a portion for rearranging the advanced articles in composite order. 95
19. In an apparatus for arranging articles, a rotatable member having a spiral way comprising a portion for properly arranging and advancing articles from an indiscriminately arranged supply thereof and a portion for rearranging the advanced articles into a group of predetermined magnitude. 100
20. In an apparatus for arranging articles, a pair of oppositely rotatable members having cooperating spiral ways for properly arranging and advancing articles from an indiscriminately arranged supply thereof, said spiral ways having cooperating portions 105 for rearranging the advanced articles into a group of predetermined magnitude. 110
